Primary Examiner — Philip S Hyder
Assistant Examiner — Sydney Buffalow(57) **CLAIM**

The ornamental design for a versatile art display, as shown and described.

DESCRIPTION

FIG. 1 is an isometric view of a versatile art display in a folded position, the versatile art display having a polygon shape; FIG. 2 is a front view of the polygon shaped versatile art display in the folded position, which is a mirror image of the back view (not shown);

FIG. 3 is a left side view of the polygon shaped versatile art display in the folded position, which is a mirror image of the right side view (not shown);

FIG. 4 is a top view of the polygon shaped versatile art display in the folded position;

FIG. 5 is a bottom view of the polygon shaped versatile art display in the folded position; and,

FIG. 6 is a top plan view of the polygon shaped versatile art display in an unfolded position.

The broken lines in FIG. 6 illustrate scored portions of the versatile art display in the unfolded positions, and form part of the claimed design.
